UNITED STATES PATENT OFFICE.

JOSEPH H. MILLS, OF RICHMOND, INDIANA.

STRUCTURAL MATERIAL.

1,075,845.

Specification of Letters Patent. Patented Oct. 14, 1913.

Application filed January 13, 1906. Serial No. 295,961.

To all whom it may concern:

Be it known that I, JOSEPH H. MILLS, a citizen of the United States, residing at Richmond, Wayne county, Indiana, have 5 invented a new and useful Structural Material, of which the following is a specification.

My invention relates to a new and useful structural material composed of wood and 10 metal to take the place of what is included under the general designation of lumber and to this end I provide structural material of any length and dimensions by building up the same from a hollow frame of wood in 15 connection with metal preferably sheet steel of suitable gage or thickness. In this manner I am enabled to produce a construction which possesses many advantages over the ordinary lumber among which advantages 20 may be mentioned comparative cheapness and lightness in weight as well as sanitary advantages and protection against fire.

As is well known the price of lumber is rapidly increasing owing to the scarcity 25 thereof or inaccessibility to the source of supply and as is also well known the price increases considerably, in board measure, in considerable proportion beyond certain lengths and widths. However, by the use of 30 my built-up structural material I am enabled to produce a construction not only equaling but exceeding in strength and rigidity lumber of the same dimensions and also a construction which is considerably 35 cheaper in price and much lighter in weight. In addition, I am enabled to utilize shorter lengths and widths of material which can be obtained at much less price than the longer lengths and wider widths. The increase of the length of my structural material 40 increases the cost only in a substantially regular ratio and the increase in the width increases the cost in a diminished ratio, whereas the increase in length and 45 width of the regular lumber causes an increase in cost in a ratio approximating a geometrical ratio. Moreover whereas the length and width of ordinary lumber are within fairly close restrictions, I am enabled 50 to produce a lumber construction of any desired width or length without being restricted to any commercial lengths and widths whatsoever. Furthermore by covering 55 the wooden frame work to a greater or less extent, as may be desired, I am enabled

to make the construction sanitary and also make it fire-proof and in addition I am enabled to provide the proper foundation for nailing. Other advantageous features of my material will be apparent from the 60 description hereinafter given and will also be hereinafter more particularly referred to after an explanation and disclosure of the invention have been made.

In the accompanying drawings Figure 1 65 is a perspective of one form of my lumber construction with the material on two opposite sides only leaving the wood of the frame work at the other two sides exposed for nailing purposes; Fig. 2 a cross section 70 of the construction shown in Fig. 1; Figs. 3, 4 and 5 cross sections of modified forms of my lumber construction; Figs. 6, 7 and 8 detailed views representing my novel method of securing the sheet metal to the wooden 75 members of the frame; Figs. 9 and 10 views of different methods for securing the sheet metal to its wooden frame; and Fig. 11 a detail of a modified form of construction.

My invention may partake of different 80 forms of construction as well as of different dimensions which different forms of construction vary more particularly because of the greater or less extent of envelopment of the wooden members or frame by the sheet 85 metal. Some of the different forms of construction which may be adopted are illustrated in Figs. 1, 3, 4 and 5 and the same will now be referred to and described in that order.

Referring to the construction illustrated in Fig. 1 and also in Fig. 2, I first provide a frame composed of the two parallel wooden members 1, 1 which may be of any desired length, width or thickness as conditions may require, or which may be built up of sections until the required length of the entire lumber construction is obtained. By preference I arrange and secure at intervals between these members 1 a series of 100 cross braces 2 so as to maintain the sheet metal in perfectly flat condition and thereby be enabled to utilize the full tensile strength of the metal, as hereinafter made apparent. Still referring to the construction shown in Fig. 1, I secure to opposite sides of this frame work the metal which is preferably sheet steel, formed in strips marked 3 and secured in suitable manner to the frame. It will be understood that the 110

metal strips may be of the same length as the completed construction or may be built up in lapped sections to the proper length to secure a continuous and unbroken breaking strain. According to this construction 5 two opposite sides, that is the narrower sides or edges, in the present instance, of the construction have the wood of the frame exposed thereby providing for nailing on the opposite edges, which construction may 10 be employed more particularly for stud-
ding, joists and similar forms of lumber.

Referring to the construction illustrated in Fig. 3, this construction is the same as 15 that of Figs. 1 and 2 with the exception that one of the edges is also covered by the sheet metal, in the present instance by continuing one of the side strips of sheet metal to form the side or edge 3^a to cover one 20 edge, the other edge being left exposed. This form of construction has the advantage over that form illustrated in Fig. 1 in that it possesses additional fire-proofing inasmuch as that edge which would 25 probably be the exposed one in actual building construction is thus covered by the sheet metal.

Referring next to the modification illustrated in Fig. 4, according to this construction 30 the sheet metal completely surrounds the wooden frame, both the metal strips in this instance being continued to form portions 3^b which envelop or cover the edges of the frame. This construction is fire- 35 proof inasmuch as the wood is not at all exposed but completely covered or surrounded by the sheet metal. In the use of this construction as well as that illustrated in Fig. 3, the nails may be driven directly 40 through the sheet metal and into the wood of the frame.

Referring next to the modification illustrated in Fig. 5, the wooden members or 45 strips are here shown as provided on one side only with the sheet metal, which is secured to said wooden strips in suitable manner, but preferably in the manner hereinafter explained in detail.

As hereinbefore suggested I prefer to 50 employ a novel and efficient method and means for securing the sheet metal to the wooden frame. Such method and means form no part of my present invention but as the formation and coöperation of tongues 55 stamped from the body of the sheet metal constitute an element in the preferred embodiment of my invention, I have illustrated the same in detail by Figs. 6, 7 and 8 of the drawings, and I will describe in 60 a general way, the mechanism for forming or stamping the tongues and pressing the same into the wood.

As shown in Figs. 6, 7 and 8 tongues 4 65 of substantially trapezoid shape are stamped from the body of the sheet metal and

hinged at its narrower side. The body of the tongue is forced downwardly into the wood and longitudinally thereof with the result that in practice the tongue occupies a position in the body of the wood at substantially right angles to its strip. Owing to the peculiar shape of the tongue and to this method of embedding the same in the body of the wood, an anchor or positive attachment is formed for the strips inasmuch as 70 owing to the widened character of the free ends of the tongues the same cannot be withdrawn from the wood except by a pressure which would disrupt the entire construction. Moreover, by this means the 75 sheet metal is held to the wood against forces exerted at every possible angle. In any event the anchorage is more firm and rigid than would be the case if nails were employed. It will be understood that a 80 series of these tongues preferably in staggered relationship may be stamped from the sheet metal strips near their opposite longitudinal edges corresponding to the positions occupied by the wooden members or strips, 85 all as clearly illustrated in Fig. 1 and also in Fig. 2. Furthermore, provision may be made for strengthening the structural material at the point or points of greatest strains by reinforcing the sheet metal at 90 such point or points. For instance, as seen in Fig. 11, which illustrates a construction of considerable length, two additional sheets or plies 3^c are employed, the same being of decreasing length so that the middle 95 portion alone shall be strengthened by the full number of sheets or plies. These plies and the number thereof will be according to the location and character of the strain to which the structural material 100 may be subjected.

The sheet metal may be secured in any suitable manner, as hereinbefore stated, and although the method illustrated in Figs. 1 to 8, in which tongues stamped therefrom 110 are anchored in the wood, will be found efficient and satisfactory in use, yet other efficient methods may be adapted, as illustrated in Figs. 9 and 10, in which one of the side strips 1 is grooved and also undercut along 115 the center of its outer surface for the purpose of receiving the inwardly turned ends 3^c of the opposite metal strips 3, it being understood that both longitudinal edges of each plate are secured or anchored in like 120 manner. While in Fig. 10 a single groove in each side strip 1 suffices for both of the opposite sheet metal strips, yet if desired each longitudinal edge of each strip 125 may be provided with its own groove, as illustrated in Fig. 10, wherein the longitudinal edges 3^c of each of the metal strips is inserted in its own groove 3^c and thereby securely held in place.

If desired my structural material may be 130

filled with cement, concrete or the like especially in case additional strength or rigidity is required or preferred. Moreover this filling of the structural material with cement may be done either at the place of manufacture of the structural material or at the place of use, that is *in situ*.

The structural material thus produced by me is capable of taking the place of ordinary lumber and possesses many advantages in addition to those mentioned, due to the fact that it is a manufactured product. For instance, it can be made of the exact dimensions required and is of course serviceable to its full dimensions, thus avoiding the waste arising in the use of ordinary lumber from cutting out defects due to "checking," or other causes; and any desired architectural form or special dimensions that may be required can be accurately made, thus avoiding the necessity incident in the case of ordinary lumber to trimming and fitting part to place. Also the employment of the sheet metal secured to the wooden frame results in so utilizing the tensile strength of the metal as to secure a particularly strong and rigid article, which is not subject to warping through the effect of weather or time to the same extent as ordinary lumber. Furthermore, the employment of my material overcomes all the disadvantages resulting in the use of ordinary lumber in house construction as respects cracking, settling, distortion and the like, and such employment of my structural material also permits the walls of a house to be

plastered and papered with safety immediately following the construction.

I claim:

1. Structural material made to commercial forms and comprising parallel wooden strips spaced apart, and two strips of sheet metal extending across and covering two opposite edges of the wooden strips, leaving two opposite sides thereof exposed for nailing purposes, both the wooden and metal strips constituting an integral structure and an article of commerce and said metallic strip having tongues stamped out therefrom and embedded into the wood for so securing the wooden and metallic strips together. 40

2. Structural material made to commercial forms and comprising two parallel wooden strips spaced apart, cross pieces for connecting the strips and spacing them, and two strips of sheet metal extending across the edges of the strips and covering the edges of the same and the cross pieces, leaving two opposite sides of said wooden strips exposed for nailing purposes, said 45 metallic strips having substantially trapezoidal-shaped tongues stamped out therefrom and embedded within the wooden strips for securing them together, and such wooden strips and cross-pieces and metal 50 strips constituting an integral structure and an article of commerce. 55

JOSEPH H. MILLS.
